UNITED STATES PATENT OFFICE.

EDWARD H. ROSE, OF FLINT, MICHIGAN.

RATCHET-WRENCH.

1,099,572.

Specification of Letters Patent.

Patented June 9, 1914.

Application filed November 9, 1912, Serial No. 730,459. Renewed December 1, 1913. Serial No. 804,115.

To all whom it may concern:

Be it known that I, EDWARD H. ROSE, a citizen of the United States, residing at Flint, in the county of Genesee and State 5 of Michigan, have invented certain new and useful Improvements in Ratchet-Wrenches, of which the following is a specification, reference being had to the accompanying drawings.

10 This invention relates to new and useful improvements in ratchet wrenches, the object of the invention being to simplify and improve the construction of such implements and produce a device of this character which 15 may be quickly reversed without moving the same from the nut or other object being actuated.

Another object of the invention is to provide a device of this character which will 20 possess advantages in points of efficiency and durability is inexpensive to manufacture and at the same time is simple in construction and operation.

With the above and other objects in view 25 the invention consists in the novel features of construction and the combination and arrangement of parts hereinafter more fully described pointed out in the claims and shown in the accompanying drawings in 30 which—

Figure 1 is a side elevation of a wrench constructed in accordance with my invention. Fig. 2 is an enlarged side elevation, the retaining plate being removed. Fig. 3 is 35 an enlarged sectional view taken on the line 3—3 of Fig. 1.

Referring more particularly to the drawings, 1 indicates the handle of the wrench having an annular head 2 formed at one 40 end thereof which is arranged with a centrally arranged circular opening 3. Arranged within the opening 3 in the head 2 is a ratchet wheel 4 having two series of teeth 5 and 6 formed upon the intermediate 45 portion thereof and disposed in opposite directions. The ratchet wheel 4 is provided with a nut receiving opening 4', it being understood that this opening may be formed in various sizes or a number of ratchet 50 wheels may be provided with each wrench, each wheel having an opening of different size so that various sizes of nuts and other objects may be manipulated with the same wrench. Formed upon each side of the 55 ratchet wheel 4 are the circular bearing

portions 7 which are adapted to be arranged in the circular openings 8 formed in the metallic plates 9 arranged upon each side of the head 2, said plates being held securely in place by means of the screw 60 bolts 10.

Formed within each face of the head 2 and arranged at opposite sides thereof are the recesses 11 which are adapted to communicate with the central opening 3. 65 Mounted within the recesses 11 for sliding movement are the pawls 12 which are adapted to engage the teeth 5 and 6. Secured to the outer periphery of the head 2 as shown at 13 are the leaf springs 14 which are arranged within the inwardly extending grooves 15, the inner ends of said grooves communicating with the recesses 11. The inner ends of the springs 14 are disposed within the recesses 16 formed in the pawls 70 and are adapted to normally hold said pawls into engagement with the ratchet wheel. The inner ends of the grooves 15 are provided with an enlargement 17 to permit a free movement of the inner ends of the 75 springs upon the reciprocation of the pawls 12.

Pivotal secured in the outer faces of the pawls 12 are the arms 18, the outer ends of which are turned outwardly and disposed 80 at right angles to the body portion as shown at 19. The outwardly turned ends 19 are arranged within the recesses 20 formed in the plates 9 and are adapted to engage with 85 in the notches 21 when it is desired to release the pawls from engagement with the teeth 5 and 6. Thus in order to disengage one of the pawls from one side of the ratchet wheel, the outwardly turned end of one of the arms is pulled out and engaged with 90 in the recess 21, thus allowing the wheel to be turned freely in one direction and in order to release the wheel so that the same may be turned freely in an opposite direction, the pawl on the opposite face of the 95 head is disengaged from the opposite set of teeth. It will be apparent that the ratchet wheel is held against rotation in either direction when both pawls are in engagement with both sets of teeth.

From the above description taken in connection with the accompanying drawings, it will be readily apparent that I have provided a simple and durable ratchet wrench which can be quickly and readily operated, 110

is extremely simple in construction and can be manufactured at a comparatively low cost.

While I have shown and described, the preferred form of my invention, it will be obvious that various changes in the details of constructions and in the proportions may be resorted to for successfully carrying my invention into practice without sacrificing any of the novel features or departing from the scope of the appended claims.

What I claim is:—

1. In a device of the character described, the combination of a handle having an annular head, a ratchet wheel rotatably mounted therein, and provided with two series of oppositely disposed teeth, plates arranged upon each side of said head, spring pressed pawls arranged upon opposite sides of the head and adapted to engage the teeth on the ratchet wheel, arms having one of their ends pivotally secured to said pawls and having their other ends extending outwardly at right angles to the body portion, said plates being provided with recesses within which the outwardly turned ends of the arms are adapted to be disposed, said plates being further provided with notches adjacent the recess to receive the outwardly turned ends and retain the pawls from en-

gagement with the teeth of the ratchet wheel.

2. In a device of the character described, the combination of a handle having an annular head, plates arranged upon each side 35 of the head, a ratchet wheel having two series of oppositely disposed teeth arranged within the head, spring pressed pawls arranged upon opposite sides of the head and adapted for reciprocatory movement to engage the teeth of the ratchet, arms having one of their ends pivotally secured to the pawls and having their other ends extending outwardly at right angles to the body portion, said plates being provided with recesses 45 within which the outwardly extending ends are arranged, said plates being further provided with recesses arranged adjacent the first recesses and within which the outwardly extending ends are arranged 50 to disengage the pawls from the teeth of the ratchet, so that either one or both of the ratchets may be disengaged from the teeth.

In testimony whereof I hereunto affix my signature in the presence of two witnesses.

EDWARD H. ROSE.
